UNITED STATES PATENT OFFICE.

HARRY M. RASMUSSEN, OF FAIRVIEW, UTAH.

RECEIPT-CUTTER.

1,236,484.

Specification of Letters Patent. Patented Aug. 14, 1917.

Application filed June 28, 1916. Serial No. 106,456.

To all whom it may concern:

Be it known that I, HARRY M. RASMUSSEN, a citizen of the United States of America, residing at Fairview, in the county 5 of Sanpete and State of Utah, have invented certain new and useful Improvements in Receipt-Cutters, of which the following is a specification, reference being had therein to the accompanying drawing.

10 This invention relates to a receipt cutter and has for its principal object the production of a device which is adapted to firmly hold the receipt upon the tray in such a manner as to permit the receipt to be torn and at the same time notched along the margin being torn, thereby indicating the amount received.

20 Another object of this invention is the production of a receipt cutter wherein the tray is adapted to fit about the receipt for holding the same against side displacement, while a clamping frame is provided which is normally urged in one direction so as to hold a plate carried thereby in a binding 25 engagement with the receipt for preventing the receipt from accidentally moving or jumping from the tray.

Another object of this invention is the production of a receipt cutter wherein the 30 slide is mounted upon the frame, this slide being provided with a notching point so that as the slide is moved transversely across the tray it may be moved to a desired position so that as the receipt is being torn 35 along the plate carried by the frame it will be notched by the slide, thus indicating the amount received.

With these and other objects in view this invention consists of certain novel combinations, constructions, and arrangements of parts as will be hereinafter fully described and claimed.

In the accompanying drawing:—

40 Figure 1 is a top plan view of the receipt cutter showing the same in position for use.

Fig. 2 is a side elevation of the receipt cutter.

Fig. 3 is an enlarged longitudinal section 50 through a portion of the receipt cutter, taken on the line 3—3 of Fig. 1.

Fig. 4 is a section taken on the line 4—4 of Fig. 2.

Fig. 5 is a detail perspective view of one

end of the clamping frame and of the plate 55 and slide.

Fig. 6 is a fragmentary perspective view of a portion of the tray, illustrating the notch formed in the side flange thereof.

Referring to the accompanying drawings 60 by numerals it will be seen that the tray is formed from a blank sheet of material and comprises a base 1, having the upwardly extending and comparatively narrow side flanges 2 formed thereon. The end flange 65 3 is bent upwardly so as to fit upon a plurality of the ends of the side flanges 2, as shown in Figs. 1 and 2, thereby forming an inclosed structure at one end. At the opposite end of the body 1 the body is continued to provide a strip 4 which is bent around the adjacent ends of the side flanges 2 opposite to the end upon which the flange 3 fits. This strip 4 is bent so as to form a cylindrical end having a horizontally extending portion 5 extending parallel to the body 1, which horizontally extending portion 5 terminates in a depending wall 6 which fits upon the base 1, as shown in Fig. 70 3. In this manner it will be seen that the 80 strips extend around and in combination with the side flanges 2 will form an inclosed spring housing, as shown in Figs. 3 and 4. From this description it will be seen that the receipts 7 may be positioned upon the 85 base 1 and will be held against side displacement by the side flanges 2, the end flange 3, and the wall 6, since these receipts will fit snugly upon the inner portions of 90 these elements.

The clamping frame comprises the spindle 8 upon which a coil spring 9 is carried, this coil spring having one end carried by the spindle 8 and extending thereinto in the usual manner, as shown at 10, while the 95 opposite end 11 of the coil spring will bear upon the strip 4, whereby the spindle 8 will be normally urged in one direction. The blocks 12 are shrunk upon or secured in any suitable manner to the ends of the spindle 8 100 and extend out through the side flanges 2, as shown in Fig. 4. The side arms 13 extend into and as a consequence are carried by the blocks 12 so as to be urged in one direction, while the blocks 14 carried upon 105 the free ends of the arms 13 are adapted to carry the strands 15 engaging the two blocks 14, as shown in Figs. 1 and 5. It will be

noted that the side flanges 2 are provided with the notches 16 intermediate their ends so that the blocks 14 may fit therein when the clamping frame is in a normal position. 5 From the foregoing description, it is, of course, obvious that the clamping frame may be swung so as to wind the spring 9 upon the spindle 8 simply by swinging the clamping frame away from the body 1 of the 10 tray. At this time it will be seen that the receipts may be interposed or removed from the tray as desired. As soon, however, as the clamping frame is released, the tension of the spring 9 will cause the same to be 15 swung to its normal position so as to allow the blocks 14 to fit within the notches 16 of the side flanges 2 and permit the strands 15 to extend transversely across the tray at a point adjacent the body.

20 The clamping plate 17 is elongated, although it presents a comparatively broad structure and has upturned ears 18 formed thereon, which ears 18 are carried upon the strands 15 so as to cause the clamping plate 17 to be pivotally mounted upon the strands 15, whereby when the clamping frame moves to its normal position the clamping plate 17 may be slightly swung so as to accommodate the position of the receipts as the plate first 25 engages the same.

30 The slide 19 has a knob 20 formed thereon through which the strands 15 extend. This slide 19 is pointed at its forward end 21 so as to permit the same to notch the 35 paper or receipt as the same is being torn along the clamping plate 17. It is obvious that this slide 19 may be moved transversely across the tray of the receipt cutter since the knob 20 will permit the slide to slide 40 along the upper surface of the plate 17 and upon the strands 15.

45 When this device is in use it will be seen that the clamping frame may be swung outwardly, as above set forth, so as to permit a number of receipts which, of course, may be of any desired nature to be positioned upon the tray and held against side displacement by the side flanges, the end flange, and the 50 wall. Upon the release of the clamping frame the clamping plate 17 will be swung into engagement with the receipts 7 thus holding the receipts in their correct position upon the tray. The clamping plate and the slide will not in the least interfere with 55 the filling out of the receipts for they will be carried adjacent the central portions of the receipts and not where it is necessary to ride upon the receipts. Furthermore, the positioning of the arms 18 upon the outer 60 sides of the flanges 2, as shown in Figs. 1, 2, and 4 will cause these arms to be positioned out of the way and not interfere with the filling out of the receipts. When it is 65 desired to notch the marginal edge of a receipt indicating the amount of money re-

ceived it will be seen that the slide may be moved along the strands 15 and over the upper surface of the clamping plate 17 to a desired position so that when the receipt is torn the pointed end 21 of the slide 19 will 70 notch the receipt because of its V-shaped construction, thus preventing unauthorized tampering with the receipt or the raising of the same, since the amount received will be positively indicated upon the marginal edge 75 thereof.

80 From the foregoing description it will be seen that a very simple and efficient receipt cutter has been constructed which is so formed as to permit the same to be easily carried in the pocket of a garment, while the construction will cause the receipts to be firmly held upon the tray without interference when the receipt is being filled out, while the plate will not only hold the receipts in position but will also facilitate the 85 moving of the slide across the receipts without injuring the receipts, while the construction of the slide is such as to permit the receipts to be notched when filled out.

90 It will further be seen that the base 1 is provided with a number of finger openings 1', as illustrated in dotted lines in Fig. 1 and also shown in Fig. 3. Thus, it will be seen that when it is desired to remove the 95 receipts either in a one-piece condition or after being torn or separated, all that it is necessary to do is to insert a finger through either of the openings desired, thereby lifting the receipts from the tray.

90

100

What is claimed is:—
1. In a receipt cutter of the class described, the combination of a tray, said tray comprising a body, upstanding side flanges formed upon said body, a strip extending 105 from said body and bent backwardly at a spaced distance and terminating in a depending wall fitting upon said body, thereby forming an inclosed housing, said tray being adapted to carry a number of receipts so as to cause said flanges and said wall to hold the receipts against side displacement, a clamping frame carried upon said tray, means carried within said housing for urging said clamping frame in one direction, 110 and means carried by said clamping frame for clamping upon the receipts carried by said tray and holding the same from movement from said tray whereby the receipts may be easily filled out.

100

115 2. In a receipt cutter of the class described, the combination of a tray, said tray comprising a body, upstanding side flanges formed upon said body, a strip extending 120 from said body and bent backwardly at a spaced distance and terminating in a depending wall fitting upon said body, thereby forming an inclosed housing, said tray being adapted to carry a number of receipts so as to cause said flanges and said wall to 130

hold the receipts against side displacement, a clamping frame carried upon said tray, means carried within said housing for urging said clamping frame in one direction, 5 means carried by said clamping frame for clamping upon the receipts carried by said tray and holding the same from movement from said tray whereby the receipts may be easily filled out, and means carried by said 10 frame for notching the receipt filled out along an edge thereof when desired.

3. In a receipt cutter of the class described, the combination of a tray, said tray comprising a body, side flanges formed upon 15 said body, an end flange formed at one end of said body and engaging the ends of said side flanges, a housing formed upon the opposite end of said body and engaged by the ends of said side flanges, said tray being 20 adapted to carry a number of receipts, a spindle carried within said housing, a coil spring carried upon said spindle and bearing upon the inner portion of said housing, whereby said spindle will be urged in one direction, blocks carried by said spindle and 25 extending through said side flanges, side arms connected to said blocks, blocks carried upon the forward ends of said arms, a strand connected to said last-mentioned blocks, said 30 side flanges being provided with alined notches, whereby said last-mentioned blocks will normally fit within said notches so as to permit said strands to be carried adjacent 35 said body, a clamping plate carried upon said strand and bearing upon the receipts 40 carried by said tray for holding the same against accidental displacement, and means carried by said strand for permitting re-

ceipts to be notched along a marginal edge as the receipts are torn and the slide engages 40 the same.

4. In a receipt cutter of the class described, the combination of a tray, said tray comprising a body, side flanges formed upon said body, an end flange formed at one end 45 of said body and engaging the ends of said side flanges, a housing formed upon the opposite end of said body and engaged by the ends of said side flanges, said tray being adapted to carry a number of receipts, a 50 spindle carried within said housing, a coil spring carried upon said spindle and bearing upon the inner portion of said housing, whereby said spindle will be urged in one direction, blocks carried by said spindle and 55 extending through said side flanges, side arms connected to said blocks, blocks carried upon the forward ends of said arms, a strand connected to said last-mentioned blocks, said 60 side flanges being provided with alined notches, whereby said last-mentioned blocks will normally fit within said notches so as to permit said strand to be carried adjacent said body, a clamping plate carried upon said strand and bearing upon the receipts 65 carried by said tray for holding the same against accidental displacement, and a slide adjustably mounted upon said strand, whereby said slide may move to an adjusted position so as to permit the receipts to be notched 70 by said slide as the same are torn along said plate.

In testimony whereof I hereunto affix my signature.

HARRY M. RASMUSSEN.
